PAPER-CLAMP FOR TYPEWRITING-MACHINES.

1,327,075.

Specification of Letters Patent.

Patented Jan. 6, 1920.

Application filed July 21, 1917. Serial No. 183,633.

To all whom it may concern:

Be it known that I, ALMA A. ZAISS, a citizen of the United States, residing at Kansas City, in the county of Jackson and State 5 of Missouri, have invented certain new and useful Improvements in Paper-Clamps for Typewriting-Machines, of which the following is a specification.

This invention relates to paper clamps 10 for typewriting machines, and is designed more especially as an improvement in the paper clamps, which in the L. C. Smith typewriting machine, are mounted slidably with relation to the scale bars at the front of 15 the platen. As well known, when an operator is manifolding and desires to correct a mistake on the copies as well as on the original without taking the sheets out of the machine, it is necessary to slide the clamps 20 off the paper at both sides, afterward replacing them, or to repress the fingers of the clamps to give access to the point of correction on the carbon copies and to hold said plates or fingers repressed while making 25 erasures on the different carbon copies. Frequently an error occurs at such a point that access can be had by slipping the right-hand clamp beyond the corresponding margins of the sheets of paper. The left-hand 30 clamp cannot be slid beyond the left-hand margins of the sheets unless the sheets are of less width than legal cap.

As legal cap is almost invariably used when making a plurality of copies, the manual repression of the fingers of the clamps 35 as above suggested, is usually resorted to when erasures are to be made. The object of the invention is to provide means to automatically latch the fingers of the clamp in repressed position and thereby enable the operator to make the necessary corrections 40 with the utmost facility.

With said object in view therefore, the invention consists in certain novel and useful features of construction and combinations of parts as hereinafter described and pointed out in the appended claims; and in order that it may be fully understood reference is to be had to the accompanying 45 drawing, in which:—

Figure 1 is a front view of the platen, platen scale and carriage scale of the L. C.

Smith typewriting machine, and the paper clamps embodying my invention.

Fig. 2, is a cross section on the line II—II 55 of Fig. 1.

Fig. 3, is an enlarged perspective view of one member of one of said paper clamps.

Fig. 4, is a fragmentary perspective view 60 of said paper clamp.

Referring to the drawing in detail, 1 are the base members and 2 the hinge members of the paper clamps, the hinge members being identical in all respects with the corresponding clamp members of the typewriter 65 named, except that the outwardly projecting lugs 3 thereof, are notched in their lower edges so as to constitute rearwardly-facing hooks 4. The base member of each clamp is mounted slidably on a bar 5 secured back of 70 and parallel with the carriage scale bar 6, the connection being made by means of hooks 7 and 8, formed on said member and engaging the upper and lower edges of said bar 5, as customary. The connection between the base member and the finger member of each clamp is the usual hinge connection produced by engagement of a hinge rod 9, with hinge loops 10 and 11 of the base member and finger member respectively, and a hinge spring 12 is mounted on said rod and at its ends respectively engages said members, as customary, to hold the finger member pressed against the platen. 75

I have provided the base member with a 80 resilient arm 13, extending upwardly forward of the scale bar and terminating at its upper end in a down-turned hook 14, and an upwardly-projecting finger piece 15 at 85 one end of said hook. The arm and hook constitute a spring catch so disposed with relation to the lug 3, that when the plate or finger is swung forward a sufficient distance to give proper access to the sheets of paper interposed between it and the platen or cylinder 16, the hook of said lug will ride over and repress the spring catch until the lower edge of the hook 14 is cleared, when the resiliency of the catch will cause it to move forward again until its hook 14 interlocks with the hook 4 and thus retains the finger in its repressed position, as indicated in dotted lines, Fig. 2, and by Fig. 4. 90

It will be understood that before the fin-

gers are swung to inoperative position as explained, the platen will be turned to advance the paper until the printing line is some distance above the highest point of the 5 ribbon-holding plate, not shown, at the center of the carriage, because when the paper is folded back, the fold line must occur below the line of printing wherein the correction is to be made as otherwise the said 10 ribbon-holding plate will interfere with the folding operation and the spreading apart of the carbon sheets and carbon copies.

While the sheets are held in the position described, the erasures on the carbon 15 copies are made, and then the latches are tripped by applying rearward pressure on the finger pieces 15 until the hooks 14 and 4 are disengaged. As this is accomplished the coil springs 12 snap their respective 20 fingers back against the paper and the latter against the platen. The platen is then turned back to dispose the line where the erasure has been, and the correction is to be made, in printing relation with the 25 type and then the proper character is typed on the original and properly reproduced on the copies.

From the above description it will be apparent that I have produced a paper 30 clamp for typewriting machines embodying the features of advantage enumerated as desirable, and while I have illustrated and described the preferred embodiment of the invention it is to be understood that I reserve 35 the right to make such changes in the form, proportion, detail construction and arrangement of the parts as properly fall within the spirit and scope of the appended claims.

I claim:

- 40 1. The combination in a typewriting machine, of a platen, a bar parallel to and adjacent the platen at one side of the line thereof where the type strike in the performance of their printing function, a slide- 45 able member on said bar, a finger hinged to and projecting from said slideable member to a point at the opposite side of the line of the platen where the type strike from that occupied by the bar, a spring for snap- 50 ping and holding the finger against paper on the platen, and means for holding the finger withdrawn from the platen to permit the paper thereon to be drawn forwardly therefrom.
- 55 2. The combination in a typewriting machine, of a platen, a bar paralleling the platen, a paper clamp comprising a base member mounted on said bar, a finger member hinged to the base member, a spring 60 tending to press the finger member toward the platen, and a latch mechanism comprising hooks carried by said base and finger members and adapted to inter-

lock when the finger member is swung forward a sufficient distance from the platen, 65 one of said hooks being adapted to yield to permit the other to pass it and then spring back to interlock with said other hook to retain the finger member in its inoperative position.

3. The combination in a typewriting machine, of a platen, a bar paralleling the platen, a paper clamp comprising a base member mounted on said bar, a finger member hinged to the base member, a spring 75 tending to press the finger member toward the platen, and a latch mechanism comprising hooks carried by said base and finger members and adapted to interlock when the finger member is swung forward a 80 sufficient distance from the platen, one of said hooks being adapted to yield to permit the other to pass it and then spring back to interlock with said other hook to retain the finger member in its inoperative position, 85 and means for tripping said hooks from engagement to permit the said spring to return the finger member to normal or operative position with relation to the platen.

4. The combination in a typewriting machine, of a platen, a bar paralleling the platen, a paper clamp comprising a base member mounted on said bar, a finger member hinged to the base member, a spring 90 tending to press the finger member toward the platen, and a latch mechanism comprising a lug projecting forwardly from the finger member and formed with a rear- 95 wardly facing hook at its lower edge and a resilient arm projecting upward and forward from the lower edge of the base member and terminating at its upper end in a downwardly and forwardly facing hook, standing normally in the plane of swinging movement of the first-named hook and 100 adapted to automatically interlock with the same when the finger member is swung forward a sufficient distance.

5. The combination in a typewriting machine, of a platen, a bar paralleling the 110 platen, a paper clamp comprising a base member mounted on said bar, a finger member hinged to the base member, a spring 115 tending to press the finger member toward the platen, and a latch mechanism comprising a lug projecting forwardly from the finger member and formed with a rear- 120 wardly facing hook at its lower edge, and a resilient arm projecting upward and forward from the lower edge of the base member and terminating at its upper end in a downwardly and forwardly facing hook, standing normally in the plane of swinging movement of the first-named hook and 125 adapted to automatically interlock with the same when the finger member is swung for-

ward a sufficient distance; said resilient arm having an upwardly projecting piece upon which pressure can be applied to repress the resilient arm and trip said hooks from engagement to permit the said spring to return the finger member to normal position with relation to the platen.

In testimony whereof I affix my signature, in the presence of two witnesses.
